UNITED STATES PATENT OFFICE.

CHARLES A. TURNER, OF UTICA, NEW YORK.

ONE-BUTTON UNION-SUIT.

1,204,615.

Specification of Letters Patent.

Patented Nov. 14, 1916.

Application filed November 8, 1915. Serial No. 60,215.

To all whom it may concern:

Be it known that I, CHARLES A. TURNER, a citizen of the United States, residing at Utica, in the county of Oneida and State of New York, have invented certain new and useful Improvements in One-Button Union-Suits, of which the following is a specification, reference being had therein to the accompanying drawing.

10 My invention relates to a one button union suit, and I declare the following to be a full, clear, concise and exact description thereof sufficient to enable anyone skilled in the art to which it appertains to make and use the same, reference being had to the accompanying drawings in which like reference characters refer to like parts throughout the specification.

15 The object of the invention is to provide a union suit that may be fastened in proper position upon the body of the wearer by a single button located on the garment in the rear of the neck.

20 The garment is designed especially for the comfort of the wearer in that it furnishes a better covering for the protection of the body, as well as the avoidance of harm resulting from the use of many buttons. Still further, the garment is so made, that it 25 can be conveniently donned, for the entering portion thereof is located adjacent the top, whereby both legs can be easily projected through the corresponding portions, the garment then drawn up as far as the chest, 30 whereupon the arms are inserted into the sleeves and the garment fastened in the back or rear of the neck by buttoning a single member or by snapping a clasp. It will be also observed that the garment eliminates all 35 possible exposure of the body, particularly where harmful in front about the chest, and especially when in a sitting position by locating the opening in the rear. This feature has also the advantage of effecting a modest 40 as well as graceful garment in appearance.

45 In designing the garment, the flap at the back portion is cut on a slight angle to about the center of the back and from there down the cut continues with a curve to the bottom 50 of the opening or crotch, which cut avoids the use of an extra flap or gusset at this portion, as heretofore, and hence the resultant economy of material and cost of manufacture. Moreover, the avoidance of the extra 55 flap or gusset at this portion of the garment,

will eliminate the double thickness of cloth at the crotch and obviate bulkiness in this section. However, if a double flap should be found desirable, a small gusset can be readily attached to the corresponding edge 60 of the garment to obtain this effect.

The flap or gusset, at the back of the garment, is designed to be sewed to one edge of the slit or opening in the rear of the garment and to extend from the top or neck portion 65 to the crotch. The flap is cut with a greater width in that part opposite the lower permanent opening of the garment, whereby to prevent the accidental opening of the same and the consequent exposition of the body. 70 As a further advantage, the long flap or gusset extending from the top or neck portion to the crotch is sewed across approximately its middle portion to the other parts of the garment, whereby the said seam will act as 75 a stay and strengthen the back of the garment. Furthermore, the long flap does away with the usual or customary slit across the back, which slit necessitates an ugly seam that not only presents a raw edge but mars 80 the general appearance of the garment.

The invention will be more fully understood by referring to the drawings in which:

Figure 1 is a front view of the garment outstretched; Fig. 2 is a rear view of the 85 garment outstretched; Fig. 3 is a detail view, showing the pattern of a flap or gusset employed; Fig. 4 is a fragment of the garment, showing the flap sewed thereto; Fig. 5 is a fragment of the garment showing a certain 90 modification thereof. Fig. 6 is a detail view enlarged of a front underlying flap employed; Fig. 7 is a detail view enlarged of a front overlying flap employed.

Referring more particularly to the drawings, the garment is knitted with a constant stitch throughout its texture, leaving, of course, the usual openings for the neck and sleeves. An aperture —1— is formed in the front portion adjacent the crotch and is 100 protected by the two small flaps 2—2 that are superimposed and sewed to the body of the garment as follows: to wit: the underlying flap 2 shown in Fig. 6 is sewed to the garment from the point A along the 105 edge thereof to the point B at which place the other flap 2 is superimposed and both flaps, shown in Figs. 6 and 7, are sewed to the garment from points B to C to D. At point D the second flap 2, illustrated in Fig. 110

7 is sewed to the garment from point D to A, whereby the side A to D is open on the underlying flap 2 and the side A to B on the overlying flap 2, to provide an opening 5 between said flaps.

The sleeves 5—5 which may be short or long to suit the taste of the wearer, are sewed into their proper places at the arm holes. The legs 6—6 are knitted continuously with the body of the garment and are closed in each instance by a seam along the lines 7—7.

The rear portion of the garment has an edge 8 on the left side, extending from the neck 14 down to about the center of the back, as at 9 on an incline and then continues on to the crotch 15, curving gracefully inward at 11. A flap or gusset 12, shown in detail in Fig. 3, and having an edge 13 conforming in contour to the edge 8 of the garment, is sewed therealong, so as to extend from the neck 14 to the crotch 15. The opposite edge 16 is left free its entire extent. The lower edge 17 of the flap 12 is sewed to the corresponding part of the garment.

The edge 19 of the garment or the one opposite the edge 8, is slit transversely for a short distance at 20 for the passage therebetween of the flap or gusset 12, whereby the upper half of the flap 12 is covered by the contiguous part 21 of the garment, and the lower half of said flap 12 will cover the like portion 22 of the garment, or in other words to reverse the position of the upper and lower portions of the gusset 12 from underlying to overlying with respect to the right hand portion of the garment adjacent the free edge 19.

40 The flap 12, the portion 21, and the lower part 22 of the garment are all sewed along the seam 23. This seam has the special advantage of acting as a stay or of strengthening the flap 12, whereby to prevent undue bagging at the crotch. Furthermore, the seam 23 allows for the opening of the garment at its upper portion or between the seam 23 and the neck 14, and at its lower portion along the edge 19 or between the seam 23 and the crotch 15, without permitting the body to be exposed, when the garment is worn.

45 The edge 19 of the garment, below the seam 23, is cut on an angle that terminates near the location where the corner 32 of the flap 12 is sewed to the body of the garment, thus avoiding a double thickness of cloth at the crotch.

50 The upper or neck part of the flap 12 is provided with a button 25, which is adapted to fasten into the button-hole 26 formed in the overlapping portion 21 of the garment. An extra button 27 is shown, although not necessary to secure the garment, but for the 55 purpose of taking up any looseness in the

neck, if the wearer should find that the button 25 when secured to the button hole 26 left any looseness thereabout.

The flap 12 is illustrated as passing from underneath to a superimposed position in relation to the part of the garment contiguous with the edge 19, yet the structure will permit the union suit to be made without slitting the edge 19 at right angles, as at 20, but still retaining the stitching therealong for strengthening the flap 12. In this instance, the flap 12 will superimpose the opposite edge of the garment and necessitate the interchange of the button and button-hole.

80 The flap 12 may be made in two pieces, if desired. In this event, the portion of the flap 12 above the seam 23 will form one piece, and the portion below the seam 23 will form the other.

85 Fig. 5 shows a modification of the garment, with respect to the addition of the gusset 27 that is seamed along the lower part of the edge 19 of the right hand side and also along the edge 17 of the flap 12, thus leaving an opening at 30, as in the former construction. The gusset 27 will with the flap 12 form a double thickness at the seat.

90 Having thus described my invention what I claim as new and desire to secure by Letters Patent is:

95 1. In a union suit, a rear portion cut from the neck at an angle to about the waist line terminating in a curve, whereby an enlarged piece is formed in the lower part of the garment, a gusset seamed to the edge of said cut to form a closed crotch, and a single member for securing said garment upon the wearer.

100 2. In a one button union suit, an unbroken front portion, a gusset disposed in the rear part, said gusset extending from the neck to the crotch, a transverse slip located at the middle portion of the garment for permitting the gusset to pass from underlying to overlying position, and a single member for fastening said garment upon the wearer.

110 3. In a one button union suit, an unbroken front portion, a gusset disposed in the rear part, said gusset being arranged to underlie the body of the garment for a portion of its length and to overlie the body of the garment for another portion, whereby to prevent undue exposure of the body, when the garment is worn.

115 4. In a one button union suit, an unbroken front portion, a gusset disposed in the rear part of said garment, extending from the neck to the crotch, said gusset being so arranged as to underlie the body of the garment for a portion of its length and to overlie the body of the garment for another portion of its length, whereby to

95

prevent the undue exposure of the body, when the garment is worn.

5. In a one button union suit, an unbroken front portion, a gusset disposed in the rear part of said garment, said gusset extending from the neck to the crotch thereof, and being so arranged as to underlie the body of the garment for a portion of its length and to overlie the body of the 10 garment for another portion of its length, and a seam for securing the body portions of the garment to the gusset, whereby to prevent undue bagging of the garment at the crotch.
- 15 6. In a one button union suit, an unbroken front portion, a gusset disposed in the rear, said gusset extending from the neck to the crotch and being arranged to

underlie the body of the garment for a portion of its length and to overlie the body of 20 the garment for another portion of its length, a seam for uniting the body of the garment to said gusset at about its middle portion, whereby to prevent undue bagging at the crotch of the garment, and a button 25 for closing said garment in the rear.

7. In a union suit, a rear portion cut from the neck at an angle to about the waist line terminating in a curve, whereby an enlarged piece is formed in the lower part of 30 the garment and a gusset seamed to the edge of said cut, whereby to form a closed crotch.

In testimony whereof I have affixed my signature.

CHARLES A. TURNER.
